ATTORNEY

UNITED STATES PATENT OFFICE

CHARLES PYRON LAUGHTER, OF LULING, TEXAS.

PUMP JACK.

Application filed December 5, 1924. Serial No. 754,068.

To all whom it may concern:

Be it known that I, CHARLES PYRON LAUGHTER, a citizen of the United States, residing at Luling, in the county of Caldwell and State of Texas, have invented certain new and useful Improvements in Pump Jacks, of which the following is a specification.

This invention relates to well pumping apparatus and refers particularly to pump jacks.

The principal object of the invention is to provide a pump jack which has an absolutely straight power operation both up and down in the well.

Another object of the invention is that it decreases the power necessary to pump a well at least 40 per cent.

The invention has also the advantage of attaining the adjustability of the length of the power stroke on the pump or polish rod to accommodate any well.

Other objects are the simplicity of the pump jack, tending towards the elimination of complicated or too numerous parts, making it practically "trouble-proof"; and its economical manufacture.

The new and improved pump jack will be more definitely and clearly understood by perusal of the following description, in connection with the accompanying drawings, and wherein:

Figure 1 is a side elevational view of the pump jack in position on a well, with part of the power wheel broken away.

Figure 2 is a top view of the power wheel, looking along the line 2-2 of Figure 1.

Figures 3 and 4 are side elevational views, respectively, of modified forms of the power wheel, the latter figure reduced in size for convenience of illustration, and showing the weight element secured directly to the wheel; and

Figure 5 is a fragmentary sectional view of the power wheel, illustrating a modification of the means for connecting and adjusting the pump rod to the wheel.

Continuing the description of the pump jack and referring to its various parts more in detail, 1 denotes one of a pair of standards upon which is mounted a shaft 2, supporting the power wheel 3.

This wheel, it will be seen, has rounded openings 4-4 in lieu of spokes, this arrangement tending to greater strength, the

openings being equally spaced around the wheel. By reference to Figure 2 it will be noticed that the wheel has a groove 5 around its periphery, adapted to receive a cable 6, the upper end of which is secured to the wheel, the lower part of the cable being connected to the polish rod 7, reciprocating within the well casing 8. A delivery pipe line is shown at 8a.

Another cable 9 is also connected to the wheel on the opposite side and likewise travels within the groove 5. On the lower end of the cable 9 is suspended a comparatively heavy weight 10 which has a box 11 extending into the ground. This weight is one of the particular features of the pump jack, and decreases the amount of power necessary to operate the pump to a great extent, and which will be more fully explained hereinafter.

Referring to Figures 1 and 3, on both sides or faces of the power wheel 3 are a pair each of rocker arms 12-12. These arms are circular in shape and are curved in line with the diameter of the wheel. They are secured to the wheel by bolts 13-13. These rocker arms as will be seen from Figure 2 stand out from the faces of the wheel and are grooved underneath for the purpose of receiving the two connections 14-14, of the jack line 15, leading to a source of power not shown. The upper rocker arms are of smaller dimensions than those directly below, the sizes providing for various lengths of stroke on the polish or pump rod. There are also provided connections 16-16 adjacent the rocker arms for the connecting of cable leads 14-14.

In Figures 3, 4 and 5 are illustrated modifications of the power wheel, weight and cable connecting means. In Figure 3 the cable may be attached by means of an eyed member 16 and on this form of wheel is a guide roller attachment 17 for the cable 9. In Figure 4 the weight 10 is fastened directly to the wheel, this arrangement being desirable on a long pull; and in Figure 5 the wheel periphery has teeth 18-18 for a link chain 19, the chain being fastened to any of the teeth by a screw cap 20.

In operation, the jack line 15 from the source of power is connected to one of the attachments 16 on the wheel and placed in the rocker arm groove, according to the length of stroke desired. The pull on the

- rocker arm communicated to the wheel 3 will cause the cable 6 on the polish or pump rod to rise and the weight 10 will move downward, and owing to the connecting 5 point of its cable on the wheel, will greatly reduce the power necessary to lift the pump or polish rod. When the weight has descended or moved around on the wheel sufficiently far or to about the point A, there 10 is a moment when the weight exerts no pulling motion on the wheel to lift the rod. In other words, it might be said that the weight is off the dead center of its pull to rotate the wheel in this direction. After 15 the "dead" point is passed, however, and the wheel reverses its rotation or rocking motion, the weight has also an appreciable pulling action on the wheel from about the point B.
- 20 It should be understood that modifications and changes may be made in the arrangement and construction of the invention without departing from the spirit and intent of the following claims:
- 25 1. A pump jack for wells comprising a wheel and a support mounted over a well, rocker arms arranged upon the wheel and adapted to receive cables from a source of power, means on the wheel for adjust- 30 ably connecting the well cable carrying the pump rod; and a weight on one side of

the wheel to aid in reciprocating the pump rod in the well.

2. A pump jack for wells comprising a wheel supported over a well, a plurality of 35 curved and grooved rocker arms on each side of the wheel adapted to receive cables from a source of power to operate the jack, means for adjustably connecting said cables to the wheel to permit the cables to track 40 in the grooves as the wheel rotates; means on the periphery of the wheel for adjustably affixing a cable and a track therefor; and a weight connected to the wheel to aid in reciprocating the pump rod in and out of 45 a well.

3. A pump jack for wells comprising a wheel mounted over a well, and having spaced apertures in lieu of spokes; rocker arms on the wheel faces for power cables; means on the periphery of the wheel for connecting a pump rod line with means to enable the line to track on the wheel; a weight connected to the wheel to assist by gravitational pull the rotation and rocking 50 motion of the wheel to reciprocate a pump rod in the well; and a guide means for the weight.

In testimony whereof I have signed my name to this specification.

CHARLES PYRON LAUGHTER
